UNITED STATES PATENT OFFICE.

JOHN E. BELL, OF BROOKLYN, NEW YORK, ASSIGNOR TO POWER SPECIALTY COMPANY,
OF NEW YORK, N. Y.

ECONOMIZER FOR STEAM-BOILERS.

1,392,675.

Specification of Letters Patent.

Patented Oct. 4, 1921.

Application filed October 20, 1920. Serial No. 418,200.

To all whom it may concern:

Be it known that I, JOHN E. BELL, a citizen of the United States of America, residing at Brooklyn, in the county of Kings and 5 State of New York, have invented certain new and useful Improvements in Economizers for Steam-Boilers, of which the following is a full, clear, and exact description.

In certain forms of economizers for steam 10 boilers it has heretofore been the practice to employ transverse tubes united at or near their ends to rectangular iron plates or blocks which are laid one upon the other in horizontal rows to form the walls of the 15 heating chamber and to connect the tubes by suitable headers outside the wall or walls thus formed.

The weight of the tubes and the rectangular end plates or blocks is very considerable 20 and when the dimensions of the structure are at all substantial the pressure between the superposed plates or blocks is so great that it becomes difficult to remove any one block and its connected tube, particularly one near 25 the lower part of the wall. This is objectionable from a practical standpoint as it frequently becomes necessary to remove a block and tube for purposes of examination or repair. The objection may in a measure be 30 avoided by supporting each horizontal row of end blocks on metal beams, but this is not feasible because of the massive character and expense of the beams which would be required to support the weight across the entire 35 wall and prevent sagging.

I have sought to overcome this objection and to construct an economizer of this kind in a more simple and economical way in which, any one or more of the end plates or 40 blocks and their connected tubes may be readily and easily removed in case the necessity arises for so doing.

According to my present invention I employ in connection with each horizontal row 45 of plates or blocks a cross beam of relatively small size upon which the plates rest and which in turn are supported by contact with the row of plates below, but with each plate I employ a peculiar wedge intermediate its 50 corners and the beam beneath which is normally forced into its position and takes up the weight of the said plates, but which may be withdrawn whenever required to permit the plate to fall upon the beam and thus be- 55 come loose so that it may be easily removed.

As each plate in the bank or wall is thus supported by the wedges the wall as a whole is as solid and has as little tendency to sag as though the plates all rested edge to edge upon themselves and the removal of the 60 wedges of one plate leaves such a short length of the cross beams to sustain the weight above it that there is no tendency to sag.

This improvement I have illustrated in 65 the accompanying drawings in which—

Figure 1 is a view in elevation of the wall composed of the end plates or blocks showing the wedges incorporated therewith. The outer walls of the structure are shown in section 70 in this figure.

Fig. 2 is a vertical sectional view of the wall and wedges.

Fig. 3 is an enlarged detail of one of the wedges.

Fig. 4 is a similar view of the wedge at 75 right angles to Fig. 3.

Fig. 5 is a detail view of a modified form of wedge and

Fig. 6 is an end view of the same.

The structure generally is of the usual character and construction and comprises a bank of tubes 1, preferably of wrought steel incased in corrugated rings of cast iron 2. To each tube near its end is joined a rectangular block or plate 3 of cast iron and the projecting ends of the tubes are properly connected by headers 4.

The walls of the tube or heating chamber are built up by the horizontal rows of end 90 plates 3, as shown in Figs. 1 and 2 and the outer wall inclosing the space which contains the headers is of the usual character and designated by 5.

Between the horizontal rows of end plates 95 3 are cross beams 6 which are properly supported in the walls or setting at their ends. These beams need not be of any greater dimension than is sufficient to support practically a single end plate upon each lineal 100 unsupported stretch that is occupied by such plate and the wall is so built up that each beam rests for its entire length upon the top edges of the horizontal row of plates beneath it.

The row of end plates above the beam are supported upon such beam, not directly, but by means of wedges the construction of which is shown in Figs. 2, 3 and 4. The end plates have cut away parts at their 110

lower corners and in these cut away portions saddles 7 are placed which span the beam 6. Over these saddles are wedges 8 with threaded extensions or bolts and when the 5 end plates are positioned, keys 9 of proper shape are inserted between the wedges and the shoulders of the cut away portions of the plates and are forced home by nuts 10 and washers 11, and thereby caused to raise 10 the end plates so that they are forced up against the cross beam above and rest upon that below.

The upper portion of Fig. 2 shows the parts before being secured in their final 15 position in which they are shown in the lower portion of the figure.

If any plate is to be removed the wedges under its lower corners are withdrawn so that it sinks away from the beam above and 20 onto the beam below. Being thus loosened it may easily be withdrawn. The end plate above it does not sink as the beam 6 upon which it rests is amply sufficient to support it as the span upon which the weight is 25 imposed is only slightly greater than the width of one plate.

The wedge shown in Fig. 3 is the preferred form, but others may be used. For example, the bolt 12 of Figs. 5 and 6 may 30 be T-shaped and the wedge 13 may be engaged by and drawn up by the bolt when the nut 10 is turned.

As above stated, the details of the construction of the structure, as a whole, are 35 not material, provided it comprises transverse tubes secured to end plates which support the tubes and which are built up in the manner described to form a wall. The

invention is particularly designed for and applicable to an economizer such as I have 40 shown in a prior application Serial No. 336,284, filed November 7, 1919, but may be used with other structures of a similar nature.

What I claim is:

1. In a structure of the kind described, the combination with a bank of tubes having end plates secured thereto and built up in horizontal rows to form a wall, of cross beams between the rows of plates and removable wedges under each plate supporting the same upon the beam beneath it. 45

2. The combination with the bank of tubes and substantially rectangular end plates secured thereto arranged in superposed horizontal rows to form a wall, each end plate having its lower corners notched or cut away, of cross beams between the horizontal rows and removable wedges between said beams and the shoulders of the notches or 50 cut away portions of the plate above. 55

3. The combination with the bank of tubes and substantially rectangular end plates secured thereto, arranged in superposed horizontal rows to form a wall, each end plate 65 having its lower corners notched or cut away, of cross beams between the horizontal rows, saddles on said beams extending through the said notches or cut away portions and wedges on said saddles and means 70 for tightening said wedges so as to support the plate above upon said beam.

In testimony whereof I hereto affix my signature.

JOHN E. BELL.
